UNITED STATES PATENT OFFICE.

MATHIAS LUTGEN, OF DUBUQUE, IOWA.

F-SHAPED BUILDING-BLOCK.

1,110,504.

Specification of Letters Patent. Patented Sept. 15, 1914.

Application filed April 24, 1913. Serial No. 763,391.

To all whom it may concern:

Be it known that I, MATHIAS LUTGEN, a citizen of the United States, residing at Dubuque, in the county of Dubuque, State of Iowa, have invented certain new and useful Improvements in F-Shaped Building-Blocks; and I do hereby declare the following to be a full, clear, and exact description of the invention, such as will enable others skilled in the art to which it appertains to make and use the same.

This invention relates to building blocks, and it more particularly relates to an improved form of ventilated wall blocks.

An object of the invention is to so form and proportion building blocks of this character that they may be united in the formation of walls of different thicknesses without impairing their efficiency, either with regard to strength or ventilating qualities.

Another object is to provide an improved building block of this character which effectually prevents the entrance of moisture to the inner wall.

Another object is to provide a building block of this character which is simple and easy to construct, convenient to handle, and comparatively inexpensive.

Other objects and advantages may be recited hereinafter in the claim.

In the accompanying drawings, which supplement this specification: Figure 1 is a perspective view, illustrating a corner of an eight-inch wall constructed of building blocks made in accordance with my invention. Fig. 2 is a perspective view of the corner of a ten-inch wall, in which blocks of the same kind and dimensions are employed as in Fig. 1, the blocks differently placed with relation to each other, so as to increase the thickness of the wall. Fig. 3 is a top plan view of one of the F-shaped blocks, and Fig. 4 is a similar view of one of the L-shaped blocks employed in connection with the F-shaped blocks in forming the corner of the wall.

Referring to these drawings, in which similar reference characters correspond with similar parts throughout the several views: Each F-shaped block consists of a main body portion 5, a right-angled end extension 6, and a right-angled middle extension 7. The face 8 of the block may be rough, polished, or of any desired configuration. Each L-shaped block 9 consists of two face portions 10 and 11 standing at right angles to each

other, and its face portion 10 is longer than its face portion 11. The L-shaped blocks 9 are employed in connection with the F-shaped blocks in the construction of ten-inch walls or other relatively thick walls, as hereinafter explained.

The general dimensions of the F-shaped blocks may be varied according to the thicknesses of the walls desired to be constructed therewith, but in the construction of eight-and-ten inch walls respectively, the following dimensions are given by way of example: The length of the base 5 is fourteen inches, the length of the end extension 6 is six inches, and the distance from the face 8 to the end of the extension 7 is four inches, while the thickness of each of these elements 5, 6 and 7 is two inches and the height may be from six to eight inches, preferably the latter. From the foregoing, it will be seen that the wing 6 extends four inches from the inner wall of the base 5, while the wing 7 extends two inches, or just half the distance to which the wing 6 extends from said inner wall. The wing 7 is located exactly at the middle of the base 5, so that when the F-shaped blocks are placed together as illustrated in Fig. 1, the wing 6 of each block is in contact with the inner wall of the opposite contiguous block, and the wings 7 of these opposite blocks have their parallel vertical surfaces in the same vertical planes. In other words, when two of these F-shaped blocks are placed together in reversed and oppositely disposed position they combine to form a rectangular building section eight by fourteen inches in horizontal area, substantially in the form of a figure 8 having two vertical air passages or chambers therethrough. However, when these blocks are placed together as illustrated in Fig. 2, the end extensions 6 of each block abut against the rectangular extension 7 of the opposite block, while the end extensions 13 of each opposite block form wings which extend oppositely on parallel planes from the rectangular middle portion, which latter constitutes a vertical air chamber. In this latter combination of the blocks, it will be seen that the extensions or wings 13 abut the L-shaped blocks to the right and left respectively, so as to form air chambers as shown.

When the F-shaped blocks are combined to form an eight-inch wall, the L-shaped blocks are dispensed with entirely; while

in forming the ten-inch wall from the same blocks, the L-shaped blocks 9 are combined therewith in the manner shown.

From the foregoing, it will be seen that I have provided a building block of this character which is fully capable of attaining the objects and advantages ascribed thereto, in a thoroughly practical and efficient manner.

I do not limit my invention to the exact details of construction, combination and arrangements of parts, as herewith illustrated and described, but my invention may only be limited by a reasonable interpretation of the claim.

15 I claim:

A building section consisting of two F-shaped blocks and two L-shaped blocks,

said F-shaped blocks being oppositely disposed and having their respective end extensions in contact with the middle extensions of each other, so as to form a rectangular body having oppositely extending projections, said L-shaped blocks being each fitted with one of its wings against an end of one of the F-shaped blocks and having its other wing fitted against the inner surface of the end portion of the other said block.

20 In testimony whereof, I affix my signature, in the presence of two witnesses.

MATHIAS LUTGEN.
